UNITED STATES PATENT OFFICE.

FARNUM F. DORSEY, OF NEW YORK, N. Y., ASSIGNOR TO ALBERT F. STAPLES, OF DORCHESTER, MASSACHUSETTS, AND CHARLES W. POTTER, OF WALTHAM, MASSACHUSETTS.

ACCOUNT-REGISTER.

No. 882,817.

Specification of Letters Patent. Patented March 24, 1908.

Application filed May 4, 1907. Serial No. 371,884.

To all whom it may concern:

Be it known that I, FARNUM F. DORSEY, a citizen of the United States, residing at New York, in the county and State of New York, have invented new and useful Improvements in Account-Registers, of which the following is a specification.

The present invention relates to account registers of the type in which a number of frames carrying bill holders are pivotally arranged on a base so as to be turned like the leaves of a book. It is common to construct such devices in such a manner that the frames may be removed, together with more or less of their connecting and operating mechanism, from the base of the cabinet in which they are used, to allow storing them in a safe place when not in use, and one object of the present invention is to so construct the frames and their supporting mechanism that the frames may readily be entirely removed from the latter and when so removed may be entirely independent both of their supporting mechanism and of each other, there being no permanent connections between the several frames or between the frames and any part of their supporting mechanism.

Another object of the invention is to produce an account register in which the frames are pivotally mounted upon a common axis so located as to secure the advantages of a normal parallel alining position of the frames, together with the absence of relative sliding movements of the frames and a convenient position of the frames under all conditions of working.

Other objects of the invention will be noted in connection with the detailed description of the illustrated embodiment thereof.

The invention consists in the features of construction and operation illustrated in the preferred embodiment thereof hereinafter described and broadly defined in the claims.

In the drawings Figure 1 is a side elevation of an account register embodying the present invention, with the end of the base cut away to show the spring connections: Fig. 2 is a vertical section of one of the bill-holder frames. Fig. 3 is a front elevation of the account register.

The illustrated embodiment of the invention comprises a number of bill-holder frames removably mounted on separate pivotally

movable frame supporting members, and a base on which the supporting members are pivoted. Each bill-holder frame comprises side bars (1), a bottom bar (2), a top bar (3), and a horizontal cross bar (4), these bars forming a framework on which a backing (5) of sheet material is fixed for the support of the bills. The bills are held against the backing in the usual manner by clips consisting of flat strips (6) of spring metal secured to the bars (4) and to lugs (7) on the bars (2). To form vertical divisions between the bill-holder spaces the backing is punched as shown in Figs. 2 and 3 to form lugs (8) and (9) which are bent up in opposite directions and engage the edges of the bills to keep them in place. The top bars (3) are provided with inclined forward surfaces to facilitate handling of the frames and to afford surfaces for index numbers.

The frame-supporting members comprise each a horizontal bar (11) on which the bottom bar (2) of the frame rests, and upright arms (12) which are beveled and notched at their ends, as shown in Fig. 1, and engage pins (13) fixed to the side bars of the frames. Pins (14) fixed in the bar (11) loosely engage holes in the bottom bar (2), and by these connections the frames and their supporting members are caused to operate as single members when the frames are in use. Each frame support is provided with downwardly-extending levers (15) journaled on fixed shafts (16). The shafts are mounted in the end portions (17) of the base and in uprights (18) on the bottom (19) of the base. Washers (20) separate the levers (15) to space them properly. Each lever (15) has a rearwardly-extending arm (21) to which is attached a tension spring (22) connected with the base. These springs tend constantly, when the frames are swung forward and down, to partially counterbalance their weight so as to facilitate the handling of the frames and to maintain them normally in upright position after they are raised by the operator. Preferably the springs are adjusted so as not to be quite strong enough to raise the frames from horizontal position, as it is desirable that the frames remain in the position to which they are moved by the operator. The frames which are forward of the shafts (16) require a constant counterbalancing by the springs and their springs are somewhat stronger than

those of the frames in the rear of the axis of support, while the arms (21) are also arranged at different angles, as shown in Fig. 1, for the same reason. The backward movement of the frames and frame supports is limited by buffers (24) mounted in lugs (23) on the base ends (17), and the frames, when in horizontal position, rest upon buffers (25).

When the frames are to be removed from the base this is done by merely raising them all simultaneously from their supports, the arms (12) yielding forward slightly to permit the pins (13) to be disengaged from the notches in the ends of the arms. The frames when so removed are entirely independent of each other and disconnected from their supporting members and they may be stored singly or in groups of different sizes as convenience may dictate. The frame supports and springs remain in operative position when the frames are removed and to replace the frames they are merely pressed down into the supports, the pins (14) engaging the holes in the bottoms of the frames while the beveled sides of the arms (12) permit the pins (13) to snap into their notches against the slight resistance of the springs. During the operation of the device the action of the springs is in the direction to maintain the pins (13) in such engagement and the frames have no tendency to separate from the supporting members.

To facilitate the simultaneous removal and replacement of the frames lugs (26) having interlocking projections and recesses are fixed to the side bars (1), and these lugs act to keep the frames in perfect alignment when handled as a mass. Hooks (27) pivoted to the rearmost frame may be engaged with pins (28) on the front frame to secure the frames together when they are to be stored together. These hooks rest when not in use against stop pins (29).

The frames, when in contact, remain always in parallel positions without intervening spaces and with their edges in alignment, owing to their being mounted on a common axis, and therefore there is no relative sliding movement of the frames nor any movement except the pivotal movement about this axis. The location of the axis substantially below the frames and in the median plane of the group insures that the frames shall never occupy positions in which one frame interferes with access to another frame. The applicant is aware that it has been proposed heretofore to mount a number of frames on a common axis located substantially on a level with the bottom of the frames and near the foremost frame, but in such a construction when all but the rearmost frames are swung down the frames so swung project upwardly in front of the lower portions of the frames remaining upright and render access to the rearmost frames incon-

venient. The present construction avoids this disadvantage, and it is rendered practicable partly by the removability of the frames from their supports, which obviates the objection to mechanism of this character which would arise if it were permanently secured to the frames, owing to its comparatively bulky character.

The invention is not limited to the details of construction and operation of the illustrated embodiment thereof, but may be embodied in other forms broadly defined in the claims.

I claim:—

1. An account register having, in combination, a plurality of independent bill-holder frames, means for movably supporting the frames, connections between the supporting means and the frames constructed to permit the ready removal and replacement of the frames, and means mounted on one of the frames for securing the frames together when so removed.

2. An account register having, in combination, a plurality of independent bill-holder frames, means for movably supporting the frames, connections between the supporting means and the frames constructed to permit the ready removal and replacement of the frames, and means for holding the frames in alignment when so removed.

3. An account register having, in combination, a plurality of independent bill-holder frames, means for movably supporting the frames, connections between the supporting means and the frames constructed to permit the ready removal and replacement of the frames, and means for securing the frames together and holding them in alignment when so removed.

4. An account register having, in combination, a plurality of independent bill-holder frames, means for movably supporting the frames, connections between the supporting means and the frames constructed to permit the ready removal and replacement of the frames, interlocking projections and recesses on the frames to hold them in alignment when so removed, and means for securing the frames together when removed.

5. An account register having, in combination, a plurality of bill-holder frames, a movable supporting member for each frame, and connections between each frame and its supporting member constructed to permit the ready removal and replacement of the frame.

6. An account register having, in combination, a plurality of bill-holder frames, a pivotally-mounted movable supporting member for each frame, and connections between each frame and its supporting member constructed to permit the ready removal and replacement of the frame.

7. An account register having, in combi-

5 nation, a plurality of independent bill-holder frames, a movable supporting member for each frame, and resilient connections between each frame and its supporting member yielding to permit the removal and replacement of the frame.

8. An account register having, in combination, a plurality of bill-holder frames, a pivotally mounted movable-supporting member for each frame, and connections between each frame and its supporting member constructed to yield by a pivotal movement of the latter to permit the ready removal and replacement of the frame.

15 9. An account register having, in combination, a plurality of bill-holder frames, a pivotally-mounted movable supporting member for each frame, springs connected with the supporting members and acting to hold the frames normally in upright position, and connections between each frame and its supporting member constructed to be disengaged by a relative movement of the parts in opposition to the action of the spring.

25 10. An account register having, in combination, a plurality of independent bill-holder frames, pivotally-movable supporting means for the frames, constructed to hold the frames in substantially parallel position with their edges in alinement, and connections between the frames and the pivotal supporting means constructed to permit the ready removal and replacement of the frames.

35 11. An account register having, in combination, a plurality of bill-holder frames, supporting means for the frames constructed to permit pivotal movement of the frames, connections between the supporting means and the frames constructed to permit the ready removal and replacement of the latter, and springs connected with the supporting means and tending to balance the frames, the supporting means having provision for maintaining the springs in operative position when the frames are removed, so that the frames may be replaced without manipulation of the springs.

45 12. An account register having, in combination, a plurality of independent bill-holder frames, a pivotally movable support for each frame, connections between each frame and its support constructed to permit the ready removal and replacement of the frame, and springs connected with the frame supports for controlling their movements.

55 13. An account register having, in combination, a plurality of independent bill-holder frames, a pivotally movable support

for each frame, connections between each frame and its support constructed to permit the ready removal and replacement of the frame, springs connected with the supports, and a stop to limit the movement of the supports under the influence of the springs to cause them to remain normally in position for the removal or replacement of the frames.

14. An account register having, in combination a plurality of independent bill-holder frames, a movable support for each frame comprising a horizontal bar and an arm at each end of the bar, and connections between the frame and the arms constructed to permit the removal and replacement of the frame by a movement substantially in the direction of the arms.

15. An account register, having in combination, a bill-holder frame, a movable support therefor embracing the lower portion of the frame and comprising a horizontal bar and two arms extending therefrom along the ends of the frame and having beveled and notched ends, and connections between the frame and the frame support, comprising pins on the frame engaging the notches in the ends of the arms.

16. An account register comprising a plurality of bill-holder frames occupying normally a substantially parallel position, a common axis located at a substantial distance from the frames and between the planes of the foremost and rearmost frames, and arms rigidly fixed to the frames and pivoted on said axis.

17. An account register comprising a plurality of bill-holder frames occupying normally a substantially parallel position, a common axis located near the central plane of the group of frames, and arms rigidly fixed to the frames and pivoted on said axis.

18. An account register having, in combination, a plurality of independent bill-holder frames, pivotal supports for the frames pivoted upon a common axis located at a substantial distance below the frames, and connections between the supports and the frames constructed to permit the ready removal and replacement of the latter.

19. An account register having, in combination, a plurality of independently-detachable bill-holder frames, and a pivotally-mounted supporting member for each frame comprising a U-shaped rod having arms detachably secured to the sides of the frames.
